STEAM TABLE

Betsy P. Skjerven, Brooklyn, N. Y.

Application January 15, 1936, Serial No. 59,182

4 Claims. (Cl. 4—163)

This invention relates to tables such as are used in massaging the body, and an object of this invention is to provide a table which can not only be used for massaging purposes, but which is also adapted for use in giving steam or vapor baths and the like without requiring the user to move to a separate room or special cabinet for that purpose.

This and other objects which will be apparent to those skilled in the art are attained by the invention which is illustrated in the accompanying drawings in which,

Fig. 1 is a perspective view of a table constructed in accordance with one embodiment of this invention, showing the steam hood in operative position over the table.

Fig. 2 is a longitudinal sectional view of the table shown in Fig. 1 with the hood located half way between operative and inoperative positions.

Fig. 3 is an end view of the table shown in Fig. 2 partly in section.

Fig. 4 is a transverse sectional view on the line 4—4 of Fig. 2, showing the hood supported in inoperative position beneath the table.

Fig. 5 is an enlarged sectional view of the hood, showing one end plate and a supporting arm in elevation.

Fig. 6 is a view partly in section from the bottom of Fig. 5, and

Fig. 7 is a bottom view of the table.

The illustrated embodiment of the present invention comprises a table 10 of suitable size for massaging purposes. A hood-supporting shaft 11 is rotatably mounted beneath and extends longitudinally of the table top. Hood-supporting bracket arms 12 are secured to the shaft adjacent each end of the table. The bracket arm at the foot of the table is secured to one edge of a substantially semi-circular end plate 13 located for movement through a slot 14 extending transversely across approximately one-half of the table near the foot thereof. The other bracket arm is similarly secured to one edge of an arcuate head plate 15 adapted to move through a slot 16 near the head of the table. The inner edge of the head plate 15 is reinforced by a channel 17.

A semi-cylindrical, sheet metal hood 18 extends between the end plates, is secured thereto and cooperates therewith in forming a hood for covering a patient reclining on the table when it is desired to give a steam or other form of vapor bath. The edges of the sheet metal hood 18 are reinforced by channels 19 which are secured thereto and are fastened at their ends to the end plates 13 and 15. The hood section 18 is movable from inoperative

to operative position through a slot 20 extending longitudinally of the table adjacent one side edge thereof and connecting the outer ends of the transverse slots 14 and 16.

While it is apparent that the present invention is adapted for giving any type of vapor bath desired, for the purposes of description it is assumed to be arranged for the giving of steam baths. For this purpose a steam boiler 21 is hung on straps 22 at one end of the table and a steam supply line 23 extends from the boiler to a steam manifold 24 extending longitudinally along the side of the table and supplying a plurality of steam inlets 25 extending through the top of the table to positions located within the hood when the latter is in the operative position shown in Fig. 1. The manifold 24 is inclined downwardly from its outer end toward the boiler for the return of condensate to the boiler by gravity. The lower end of the manifold is connected to a condensate return pipe 26 leading back to the boiler, as shown in Fig. 3. The steam boiler is also connected by a steam line 27 to the bottom of a cabinet 28 for heating towels or for some similar purpose and a condensate return 29 connects the bottom of the cabinet with the boiler. A three-way valve 30 is provided for controlling the flow of steam from the boiler to either or both the steam manifold and towel cabinet, or for shutting off the supply of steam entirely.

Movement of the hood from operative position shown in Fig. 1 to inoperative position shown in Fig. 4, in which the hood, while still supported entirely from the table, is suspended beneath the table so as to be out of the way, is accomplished by rotating the hood-supporting shaft 11. Any desired type of mechanism can be employed for this purpose, such, for example, as the counter balanced crank arm 31 secured to a projecting end of the shaft 11 and having a counter balance 32 for counter balancing the weight of the hood to permit easy rotation of the shaft.

Operation of the device and the method of its use will be apparent. It is to be noted that the slot 16 through which the arcuate head plate 15 moves is spaced from the head of the table a distance sufficient to provide a head rest 33 for the user. When the hood is in the inoperative position shown in Fig. 4, beneath the table, it is entirely out of the way and yet takes up no more space in the room than that occupied by the table itself. When the table is to be used for a steam or other type of vapor bath, the crank 31 is operated to rotate the hood-supporting shaft and move the hood through the intermediate position

shown in Figs. 2 and 3 to the operative position shown in Fig. 1 in which the free edge of the hood rests on the table top and forms with the table top an enclosed cabinet. This movement of the hood from inoperative to operative position, and vice versa, is accomplished without causing the hood at any time to project beyond the confines of the table edge. In other words, the device is operative without requiring any space in the room other than that taken up by the table alone. The patient's head on the head rest 33 is outside of the steam hood and towels or the like can be secured to the inner flange 17 of the arcuate head piece to prevent the escape of steam.

15 It will be apparent that the invention can be variously modified within the scope of the appended claims.

I claim:—

1. An article of manufacture comprising a table, a hood adapted to cover a person reclining on said table and to cooperate with the table top to form a vapor bath cabinet, a hood-supporting shaft mounted on said table, hood-supporting arms mounted on said shaft, end plates mounted 25 on said arms for movement through slots extending transversely of the table, a semi-cylindrical body member supported between said end plates and movable through a longitudinally extending slot in said table and means for moving 30 the hood formed thereby into and out of operative position over the table.
2. An article of manufacture comprising a table, a hood cooperating with the top of said table to form a vapor bath cabinet for the treatment 35 of a person reclining on said table, a source of steam, a steam manifold connected to said source of steam and extending along said table in an upwardly inclined direction, steam inlets connecting said manifold with the interior of said cabinet, and a condensate return connecting the lower end of said manifold with said source of steam.
3. An article of manufacture comprising a

table having a substantially unobstructed top adapted to be used for massage purposes and provided with a transverse slot extending part way across said table spaced from one end thereof sufficiently to provide a head rest between said slot and the end of said table and a longitudinal slot extending lengthwise of said table adjacent one edge thereof and communicating with said transverse slot, a hood including a substantially semi-cylindrical body portion slidable through 10 said longitudinally extending slot from an inoperative position beneath said table top to an operative position over said table top in which it cooperates therewith to form a bath cabinet, end plates connected to said body portion including 15 an arcuate end plate movable through said transverse slot, means beneath said table top connected to said end plates for movably supporting said hood, and means for moving said hood from one position to the other.

20 4. An article of manufacture comprising a table having a substantially unobstructed top adapted to be used for massage purposes and provided with spaced transverse slots extending part way across said table top, one of said slots 25 being located adjacent one end of said table and the other of said slots being spaced from the other end of said table a distance sufficient to provide a head rest between said slot and the end of said table, a hood including a substantially semi-cylindrical body portion movable from an inoperative position beneath said table top to an operative position over said table top in which it cooperates therewith to form a bath cabinet, end plates connected to said body portion and 30 movable through said slots including an arcuate end plate movable through said second mentioned slot, a hood supporting rod beneath said table top, means connected to said end plates for supporting said hood on said rod for movement 40 from one position to the other.

BETSY P. SKJERVEN.
